J. H. SMITH

GAS BURNER

Filed March 3, 1927

Jay H. Smith Inventor

By Cadmus & Co.

Attorney

UNITED STATES PATENT OFFICE.

JAY HARLEY SMITH, OF GLENDALE, CALIFORNIA.

GAS BURNER.

Application filed March 3, 1927. Serial No. 172,384.

This invention relates to a gas burner, one of the objects being to provide a simple and compact device of this character adapted to be adjusted readily so as to adapt the burner 5 for use in connection with artificial, natural or mixed gases, means being employed whereby after an adjustment, the parts can be firmly held so as to insure maintenance of the desired mixture of air and gas.

With the foregoing and other objects in view which will appear as the description proceeds, the invention resides in the combination and arrangement of parts and in the details of construction hereinafter described 15 and claimed, it being understood that changes in the precise embodiment of the invention herein disclosed may be made within the scope of what is claimed, without departing from the spirit of the invention.

In the accompanying drawings, the preferred form of the invention has been shown,

In said drawings,

Figure 1 is an elevation of a burner, the supply pipe engaged thereby being shown in section.

Figure 2 is a section through the burner taken on the line 2-2, Figure 3.

Figure 3 is a section on line 3-3, Figure 2.

Figure 4 is a plan view of the lower end of the burner.

Figure 5 is a section on line 5-5, Figure 2.

Referring to the figures by characters of reference 1 designates the base of the burner in the form of a screw plug having an annular collar 2, there being a tubular nozzle 3 integral with this plug and provided, close 35 to the collar 2 with diametrically opposed air inlet ports 4. The tubular stem 3 is exteriorly screw threaded as shown at 5, the threads extending to the port 4 and for a desired distance along the stem. Engaging

the threads 5 is a nut 6 having a skirt 7 45 adapted to partly or entirely close the ports 4 when the nut is projected in one direction along the threaded portion. A lock nut 8 is mounted on the stem and is designed to engage the nut 6 so as to hold it against 50 displacement after being adjusted. A small orifice 9 is provided in the plug 1 between the ends thereof and a passage 10 tapers toward this orifice from the lower or outer end of the plug while another passage 11 55 tapers toward the orifice from the other end of the plug, this latter passage being in communication with the passage 12 in the stem 3.

Obviously by adjusting the skirt 7 relative to the ports 4 the amount of air admitted to the passage 12 can be regulated. Thus the burner can be adapted for use with different kinds of gas and after the skirt has been adjusted it can be held securely in such 60 position by means of a lock nut 8.

What is claimed is:

A burner including a tubular base exteriorly screw threaded having an angular head, said base constituting a screw plug, there 70 being an orifice opening through the base, a tubular nozzle integral with the base, said nozzle having an enlarged exteriorly screw threaded portion extending from the base toward the center of the nozzle, there being 75 opposed air inlet ports in the threaded portion of the nozzle extending to the base, a nut slidable over the nozzle into engagement with the enlarged threaded portion thereof, said nut having a skirt movable to partly or 80 entirely cover the air inlet port, and a lock nut slidable over the nozzle into engagement with the enlarged threaded portion thereof.

In testimony that I claim the foregoing as my own, I have hereto affixed my signature. 85

JAY HARLEY SMITH.
